UNITED STATES PATENT OFFICE.

GEORGE E. NORRIS, OF TROY, NEW YORK.

MACHINE FOR TURNING CUFF-BLANKS.

SPECIFICATION forming part of Letters Patent No. 520,535, dated May 29, 1894.

Application filed October 27, 1893. Serial No. 489,245. (No model.)

To all whom it may concern:

Be it known that I, GEORGE E. NORRIS, of Troy, in the county of Rensselaer and State of New York, have invented new and useful 5 Improvements in Machines for Turning Cuff-Blanks, of which the following is a specification.

This invention relates to improvements on machines for folding blanks for cuffs, and 10 other similar articles, and the object of my invention is to provide facilities for turning the edges of said blanks mechanically. I attain this object by the mechanism illustrated in the accompanying drawings which are 15 herein referred to and form part of this specification.

In said drawings, Figure 1 is a plan view of my cuff-blank folding machine, removed from its supporting-frame, and showing the tem- 20 plet in its rearward position. Fig. 2 is a like view, showing the templet moved forward to a position for effecting the preliminary turning up of the edges of a cuff-blank. Fig. 3 is an end elevation of my machine sup- 25 ported on a frame (the latter being shown broken apart). Fig. 4 is a front elevation of my machine removed from its supporting-frame. Fig. 5 is a longitudinal section of Fig. 2 at the line X X. Figs. 6, 7, and 8 are 30 enlarged details showing different positions of the folding mechanism in the operation of folding a cuff-blank. Fig. 9 is an enlarged detail of one of the spring-guides for the cuff-blank; and Fig. 10 is a detached detail of a 35 sliding-plate for imparting movement to the folding mechanism.

As illustrated in the drawings, my machine is adapted to folding cuff-blanks for making cuffs with rounded corners, but it is equally 40 adaptable for other forms of cuffs without further invention.

As represented in the drawings, A designates the bed-piece of my machine, which can be made in the form shown, or in any other 45 form suited to the purpose.

B designates a movable-bed that is fitted to acquire a slight vertical movement in an opening, 1, formed in the top of the bed-piece A, said movement being given for effecting the 50 pressing-down of the folds formed on the edges of cuff-blanks by the folding mechanism. The movable-bed B is maintained in a

suitable heated condition by means of jets of mixed illuminating-gas and air, which are emitted from a perforated pipe, 2, arranged 55 directly beneath said bed; said heating arrangement, being old and well-known, forms no part of this invention.

C designates a sliding-plate that is fitted to move in a recess, 3, formed in the top of the 60 bed-piece A, and said sliding-plate is provided with studs which carry friction-rollers, 4, on its upper face; pendent from the lower face of said sliding-plate, lugs, 5, are formed, and a rocker-shaft, D, is journaled on said bed-piece and is provided with a double arm, 6, having a roller, 7, pivoted thereto and fitted to engage between the lugs 5 for the purpose of imparting a sliding movement to the plate C, a handle, 8, being secured to the shaft D 70 for the purpose of imparting a rocking movement to said shaft.

E designates a pair of folding-plates that are arranged to slide diagonally on the top of the bed-piece A; said folding-plates are held down, 75 to resist the upward pressure of the movable-bed B, by means of bars, F and G, the first of which is arranged longitudinally, and the others transversely on said bed-piece, upon which they are secured by bolts, 9, so as to allow the 80 plates E to slide easily; at the outer end of each of said folding-plates a pair of swinging-links, 10, is arranged to produce a diagonal movement of said plates, one end of each of said links being pivoted to the corresponding 85 folding-plate, and the opposite end being pivoted to the bed-piece A by the pivot-bolts, 11, which are adjustable in holes, 12, in the bed-piece, so as to adapt the machine for folding blanks for different lengths of cuffs. An 90 opening, 13, is formed in each folding-plate for the purpose of allowing a diagonal movement of said plate notwithstanding the bolts 9 at the ends of the bar F. The adjacent ends of the folding-plates E are slotted, as at 95 14, to receive the friction-rollers 4 of the sliding-plate, so that the movement of the latter will effect a simultaneous movement of the folding-plates, the direct inward and outward movements of the sliding-plate C being converted into diagonal movements of the folding-plates E by means of the links 10. At the inner end—or the end which abuts against the other folding-plate—a detachable piece,

15, is attached to each folding-plate so as to adapt the pair of folding-plates to meet centrally when adjusted for folding blanks for cuffs of different lengths; said detachable 5 pieces being attached to the folding-plates by means of bolts, 16, and dowel-pins, 17—both of which are indicated by dotted lines in Fig. 1. The inner portion of each folding-plate is cut out, as at 18, to conform to the shape of 10 a cuff to be folded thereby, and a recessed edge is formed about the cut out portion to produce a ledge, 19, on which the material for a blank can be laid in place preparatory to the operation of forming the fold on the blank, but, when preferred, said folding-plates may be made without the ledge 19, and other provision may be made for fixing the blanks in 15 a required place, as for instance, pins or stops may be fixed on the folding-plates to indicate 20 the position of the blanks thereon.

H designates a templet, or form, of sheet metal, corresponding to the form of the folded cuff-blank, which is attached to a plate, 20, of wood or other material, that is secured to 25 the swinging end of a bracket, 21, hinged, as at 22, to a slide, 23, arranged to move on guide-bars, 24, projecting rearwardly from the movable-bed B, and provided with a cross-bar, 25, which forms a stop for limiting the 30 rearward movement of said slide; the slide 23 is provided with lugs, 26, which form part of the hinge-joint for the bracket 21, and which may be arranged to take against stop-bolts, 27, adjustably inserted in the bed-piece A for 35 the purpose of limiting the forward movement of the slide 23. The bracket 21 is provided with a knob, 28, or other handle, to enable an operator to manipulate said bracket and the slide 23 to which said bracket is hinged.

40 I designates adjustable spring-guides which are fitted in grooves, 29, in the top of the movable-bed B and are provided with slotted openings for receiving bolts, 30, whereby said guides can be secured at any required point 45 of their movement; the free end of each of said guides is bent downward, as at 31, to form a shoulder against which the rearmost edge of the unfolded blank will take in the operation of placing the blanks in the machine.

50 It should be understood that the object of making the guides I adjustable is to adapt the machine for blanks of different widths.

The downward bend of the guide I is arranged to lie in an opening, 32, in the movable-bed B in such manner that the arm of 55 said guide can be pressed down into the groove 29 so that no part of said guide will project above the plane of the top of the movable-bed B.

60 J designates levers fulcrumed, as at 33, to the bed-piece A, and so arranged that the shorter end of each lever will form a bearing for the movable-bed B, and to make said shorter ends adjustable bearings for the movable-bed, each of them is provided with a 65 spring-plate, 34, which will bear directly against the lower part of said bed, and set-

bolts, 35, are arranged to bear against the under side of the plate 34; the longer ends of said levers are arranged to be adjacent to 70 each other so that a collar, 36, on the rod 37, will bear upon the adjacent ends of both levers. The rod 37 is connected to a treadle, 38, arranged under the machine so that the foot of the operative can be readily applied thereto for the purpose of moving the levers J to press the movable-bed B upward, the downward movement of said bed being effected by gravity, or by any other suitable means.

K designates a table or frame on which the machine rests, but the form of said table may be changed as may be desired.

The rod 37 is preferably connected to an adjustable eye-bolt, 39, for regulating the distance between the treadle 38 and the levers J, but, when preferred, the rod 37 can be provided with any of the well-known means for effecting adjustment of the distance between the treadle and levers.

My invention operates in the following manner: The folding-plates E being adjusted to a particular size of cuffs (and it being understood that the lengths of cuffs vary about a half inch in length between the different sizes, 95 the detachable pieces 15 can be made to vary a quarter inch in thickness, to compensate for the different lengths of the cuff-blanks and effect a central meeting of the folding-plates when adjusted for different lengths of cuff-blanks,) a cuff-blank of the required length is placed on the ledge 19 of the folding-plates and the opposite edge of the cuff-blank is fixed against the guides I; the templet H being raised up—as indicated by dotted lines 105 in Fig. 3—so as to clear the guides I, the operative draws the slide 23 forward, to bring the templet into position over the opening 18 of the folding-plates E; and then depresses the templet H, thereby pressing the cuff-blank 110 down onto the top of the movable-bed B and turning up the material of the cuff-blank to form an up-turned flange, 40, at the edge of said blank, as shown in Figs. 5 and 8; then, by means of the shaft D, and its attached 115 parts, the operative moves the folding-plates E—in the manner previously described—to fold said flange down against the body of the blank, as indicated by dotted lines in Fig. 7, after which the templet H is withdrawn from 120 the folded blank, and the operative, by pressing down the treadle 38, moves the levers J to raise the movable-bed B, and thereby the cuff-blank will be pressed against the under side of the folding-plates E with sufficient 125 force to complete the pressing down of the folds at the edge of the cuff-blank. By the inward movement of the folding-plates the surplus material around the rounded corners of the cuff-blank will be crimped in such 130 manner that the subsequent pressure applied by the heated movable-bed B will effectually press out the crimps. After the blank has been subjected to a sufficient pressure, the

folding-plates E are moved back to their normal position, and the movable-bed B returns to its normal position, thereby leaving the machine in condition for a repetition of the 5 operation just described.

What I claim as my invention, and desire to secure by Letters Patent, is—

1. In a machine for folding cuff-blanks, the combination of a bed-piece, a movable head 10 fitted to slide vertically in an opening in said bed-piece, a pair of folding-plates arranged to move diagonally toward each other, swinging-links pivoted to said folding-plates and bed-piece; said folding-plates having an opening 15 which conforms to the shape of the folded cuff-blank, a templet having the form of a folded cuff-blank and arranged to be moved over and depressed into the opening of said folding-plates, and levers fitted to press the movable-bed upwardly against the lower face of said folding-plates, substantially as specified.
2. In a machine for folding cuff-blanks, the combination of a bed-piece, a pair of folding-plates fitted to move diagonally toward each 20 other; each of said folding-plates being pivotally connected to one end of a pair of swinging-links which have their opposite ends adjustably pivoted to said bed-piece, and a sliding-plate fitted to move transversely on said 25 bed-piece and to impart corresponding movements to said folding-plates, as and for the purpose specified.
3. In a machine for folding cuff-blanks, the combination of a bed having grooves in its 30 upper face, adjustable spring-guides which

are depressible in said grooves, a pair of diagonally-sliding folding-plates provided with an opening which conforms to the form of a folded cuff-blank, and a templet that conforms to the shape of a folded cuff-blank and is depressible into the opening of said folding-plates; whereby an initial fold will be formed on the edge of a cuff-blank, as and for the purpose specified. 40

4. In a machine for folding cuff-blanks, a 45 pair of folding-plates arranged to move toward each other and each having a detachable piece attached to their contacting ends; whereby said folding-plates can be adapted to folding cuff-blanks of different lengths, substantially 50 as specified.

5. In a machine for folding cuff-blanks, the combination of a pair of folding-plates connected to the bed-piece of the machine by means of swinging-links and fitted to move 55 diagonally toward each other; the abutting end of each of said folding-plates having a slotted-opening formed therein, a sliding-plate fitted to move in the bed-piece of the machine and provided with studs fitted to 60 take in said slotted-openings, and a rocker-shaft provided with an arm adapted to engage with said sliding-plate in such manner that a reciprocating movement can thereby be imparted to the latter, as and for the purpose 65 specified.

GEORGE E. NORRIS.
